UNITED STATES PATENT OFFICE.

ROBERT M. HOVEY, OF NEW YORK, N. Y., ASSIGNOR TO WM. H. JACKSON & CO., OF SAME PLACE.

DESIGN FOR A FIREPLACE-FRONT.

SPECIFICATION forming part of Design No. 21,725, dated July 19, 1892.

Application filed April 21, 1892. Serial No. 430,156. Term of patent 7 years.

To all whom it may concern:

Be it known that I, ROBERT M. HOVEY, a citizen of the United States, residing at New York, in the county and State of New York, 5 have invented and produced a new and original Design for Fireplace Facings and Grates, of which the following is a full, clear, and exact specification, reference being had to the accompanying drawings, forming part thereof.

10 Figure 1 represents a front elevation of this newly-designed facing and grate. Fig. 2 represents a transverse vertical section of the same, and Fig. 3 is a horizontal section taken at line A B of Fig. 1.

15 The prominent or characteristic features of this novel design comprise representations of projecting molded cornice with dentals, a central "Adams fan" or "sunburst," acanthus-leaves, paneled frieze and pilasters, and 20 tapering half-columns with cornices and globular finials or heads in front of the projecting lower half of the side facings or pilasters. The molded denticulated projecting cornice C rests upon the frieze D, which is bordered 25 with beaded moldings and at its center is ornamented with the "Colonial sunburst" F and with acanthus-leaves E at its ends. The upper portion of the two panels G of the pilasters are likewise bordered with beaded 30 moldings, and at their union with the frieze terminate in diagonally-arranged acanthus-

leaves. The lower half of the side casings or pilasters are widened and project in front of the paneled upper half and are partly covered by half-circle projecting columns H. The 35 grate I is formed of horizontal bars in front and curved bottom bars J, and it projects as shown in Fig. 2. The columns H rest on square bases K and have projecting molded cornices or caps on which the globes or finials 40 L are seated. Below the grate a crown-plate M, having a series of square openings and checkered squares at its ends, extends between the bases of the columns below the grate.

I claim as my invention—

The design for a fireplace-front, as shown and described, the same comprising the representation of a molded denticulated projecting cornice over figures in relief of "Colonial sunburst" and acanthus-leaves on the frieze, 50 figures representing vertical columns in relief on the lower half of the pilasters with caps, rectangular bases, and globular finials, and below the figure of a grate the figure of a crown-plate with openings and checkered 55 squares and representations of beaded border-moldings, forming altogether the figure of an ornamental rectangular fireplace-front.

ROBERT M. HOVEY.
